Frank L. Allen
ATTORNEY.

UNITED STATES PATENT OFFICE.

HENRY O. HOUCK, OF HARRISBURG, PENNSYLVANIA.

DESIGN FOR A KNIFE AND FORK REST.

Application filed October 25, 1927. Serial No. 23,876. Term of patent 7 years.

To all whom it may concern:

Be it known that I, HENRY O. HOUCK, a citizen of the United States of America, residing at Penbrook, Harrisburg, in the county of Dauphin and State of Pennsylvania, have invented a new, original, and ornamental Design for a Knife and Fork Rest, of which the following is a specification, reference being had to the accompanying drawings, forming part thereof.

I claim:

The ornamental design for a knife and fork rest, as shown.

HENRY O. HOUCK.
